(57) **CLAIM**

The ornamental design for a connector barrel of a battery module, as shown and described in FIGS. 1-8.

DESCRIPTION

FIG. 1 is a back underside perspective view of a connector barrel showing our new design;

FIG. 2 is a front overhead perspective view of the connector barrel of FIG. 1;

FIG. 3 is a top plan view of the connector barrel of FIG. 1;

FIG. 4 is a bottom plan view of the connector barrel of FIG. 1;

FIG. 5 is a right side elevational view of the connector barrel of FIG. 1;

FIG. 6 is a left side elevational view of the connector barrel of FIG. 1;

FIG. 7 is a front elevational view of the connector barrel of FIG. 1; and,

FIG. 8 is a back elevational view of the connector barrel of FIG. 1.

The broken lines shown in the drawings show portions of the battery module connector barrel which form no part of the claimed design.
